(57) **CLAIM**

The ornamental design for a step frame, as shown and described.

DESCRIPTION

FIG. 1 is a front perspective view of the step frame of the present invention;

FIG. 2 is a rear view thereof;

FIG. 3 is a front view thereof;

FIG. 4 is a left-side view thereof;

FIG. 5 is a right-side view thereof;

FIG. 6 is a top plan view thereof; and,

FIG. 7 is a bottom plan view thereof.

The stippling represents a contrast in appearance by a non-slip material compared with the rest of the steps.

The dot-dashed broken lines shown in the figures are for the purpose of illustrating boundaries of the claimed design and form no part of the claimed design.
